UNITED STATES PATENT OFFICE.

HENRY CULL, OF CHICAGO, ILLINOIS.

HOISTING AND DISTRIBUTING MECHANISM.

1,178,498.

Specification of Letters Patent. Patented Apr. 11, 1916.

Original application filed October 20, 1913, Serial No. 796,140. Divided and this application filed April 22, 1915. Serial No. 23,098.

To all whom it may concern:

Be it known that I, HENRY CULL, a citizen of the United States, and a resident of the city of Chicago, in the county of Cook 5 and State of Illinois, have invented certain new and useful Improvements in Hoisting and Distributing Mechanisms; and I do hereby declare that the following is a full, clear, and exact description of the same, 10 reference being had to the accompanying drawings, and to the numerals of reference marked thereon, which form a part of this specification.

This invention constitutes a division of 15 my copending application for patent for "material elevators", filed October 20th, 1913, Serial No. 796,140.

The erection of modern buildings progresses very rapidly, and it is essential that 20 the means of hoisting and distributing the building material be capable of extension with the increase in height of the building, so that the workmen are not inconvenienced, and the material is transported directly to 25 the point of use at the various different floors of the building. Furthermore this mechanism displaces to a large extent the inefficient cage or material elevator, as well as the well known derrick boom construction, which is not only unwieldy, but dangerous.

This invention has for its object the construction of an elevating device and distributing mechanism whereby the materials 35 used or required for the construction of a building are elevated in wagon or truck loads from the street to the floor where required, and then delivered by means of the distributing mechanism to any point desired, the hoisting and distributing mechanisms being connected with the same source 40 of power.

It is also an object of this invention to afford a construction wherein a load is elevated in close proximity with the building 45 and prevented from swinging to any extent and is capable of being swung into the building structure at any floor for movement by a distributing mechanism to a point 50 desired.

It is furthermore an object of this invention to afford a construction embracing a sectional upright frame for the hoisting mechanism which may be built up from 55 floor to floor with the progress of erection

of the building, and with driving mechanisms built up from floor to floor for the distributing means on each floor maintained in operation or not, as desired, until the building is entirely completed. 60

It is finally an object of this invention to afford in connection with a hoisting device means for delivering the load where required on any floor of the building structure and to utilize the same source of power in 65 the movement of the load upon the floor as in the hoisting of the load thereto.

The invention (in a preferred form) is illustrated in the drawings and hereinafter more fully described. 70

In the drawings: Figure 1 is a side elevation of a building under construction equipped with hoisting and distributing mechanisms embodying the principles of my invention. Fig. 2 is a front elevation thereof. Fig. 3 is a top plan view of the same. Fig. 4 is a detail section taken on line 4-4 of Fig. 2. 75

As shown in the drawings: A building frame of structural steel or other material 80 comprising suitable horizontal floor members, beams, or joists 1, and uprights or posts 2, constructed as usual, or in any suitable manner, is shown in a state of partial completion. Secured at the outer side 85 of one of the uprights or posts 2, at any convenient position to permit delivery of material at the bottom thereof, is an upright guide-way 3, for an elevator or crane. This, as shown, comprises a column, preferably 90 constructed of structural steel, rectangular in cross-section, and of considerable width as compared with its depth, having recessed in the outer surface thereof upwardly facing ratchet teeth 4. Said upright column 95 or guide-way is spaced outwardly from the column or post 2, by means of locks 5, interposed between the same and the column at each successive floor of the building or at other intervals in the building height, 100 said guide-way being constructed of a plurality of duplicate interchangeable sections which are lapped or spliced together, or in any manner suitably and rigidly connected in alignment to afford a substantially continuous column with a continuous row of 105 upwardly and outwardly facing ratchet teeth thereon.

A hoisting beam 6, comprising a suitable bar, provided with a yoke 7, at its inner end, 110

is engaged on each side of a central column 2, as clearly shown in Figs. 1 and 3, inclined upwardly to the upper end of the upper section of the ratchet guideway 3, and is rigidly bolted thereto and projects beyond the same as shown in Fig. 1, and carries at its outer end a hoisting sheave 8. Mounted to slide on said ratchet guide-way is a frame 9, which may be constructed of cast steel or any suitable material recessed on its rear side to a depth to receive the guide-way 3, therein, and engaged on the rear side thereof and overlapping the rear surface of said guide-way are plates 10, which confine said frame 9, to said ratchet guide-way, but permit the same to slide freely thereon. Integrally connected to the frame 9, at the upper end thereof, and extending outwardly above the same and in the same plane therewith, is a crank arm 11, the upper end of which is turned outwardly and extends for some distance from said frame, and is provided with a plurality of apertures at different distances from said frame to enable a hoisting cable 12, to be suitably connected thereto approximately in line with the center of gravity of the mass to be hoisted. On the outer face of said frame 9, and integrally connected therewith are sleeves 13, positioned near the top of said frame and at each side thereof, and with the axes of the sleeves extending vertically, and directly beneath each of said sleeves and also integral with the frame, are socket members 14. Rotatably mounted in said sleeves and in the socket members provided, are cylindrical shafts 15, which are provided on their upper ends with integral upwardly and outwardly extending crane arms 16, having a plurality of apertures therein.

A pawl 17, is pivoted in the lower end of the frame 9, and is provided with a weight 18, which normally impels said pawl into engagement with the ratchet teeth 4, of the guide-way. A lever 19, is connected to the pawl 17, and is pivoted with a cable 20, which is led upwardly on the frame 9, to permit the pawl to be retracted when it is desired to lower the device. Mounted at the ground level of the building is an engine 21, connected to drive a hoist winch 22 and trained about said hoist winch is the cable 12, which, as before described, is trained through the sheave at the upper end of the beam 6. The winch shaft is adapted to drive a horizontal shaft 23, mounted in suitable bearings with a clutch 24, pivoted for disconnecting the drive between the shaft 23, and the winch shaft when desired. The end of the horizontal shaft 23, is adjacent a corner column 2, being supported in a detachable bearing bracket 24^a connected on said column, and journaled vertically beside said corner column in suitable bearings is a sectional shaft 25, which, at its lower end,

is provided with a bevel gear 26, meshing with a bevel gear 27, secured on the end of the horizontal shaft 23. The sections of the shaft 25, are approximately of floor height in length, and at the point of junction of the respective sections, are provided with winding drums 28.

Snatch blocks 29, are attached wherever required on the various columns 2, at different floors of the building, and a line or cable 30, is trained therethrough and looped around a winding drum 28, to be utilized as a power means for shifting a load on the different floors of the building. For this purpose a portable track 31, consisting of relatively short sections, may be laid upon the flower if desired, or over a false floor, which is sometimes constructed during the progress of erection of a building, and a truck may be provided to roll on said track and receive the load thereon elevated from the ground by the elevating mechanism. It is not essential, however, that a track and truck be provided, as the load may be deposited upon suitable rollers 32, such as shown in Fig. 2, and hauled by the cable to the point desired.

The building material is delivered, as usual, in loads at the foot of the ratchet guideway, and the operator, by pulling upon the line 20, trips the pawl and permits the frame to be lowered conveniently to the load. The entire wagon body, which is denoted by the reference numeral 32, is elevated from the vehicle frame, suitable cables being passed around the body and connected to an equalizing bar 34, depending from one of the crane arms 16, as clearly shown in Fig. 2. Inasmuch as there are two crane arms, one thereof may be equipped with a suitable chain or tackle 35, for engagement with objects which may not be conveniently hoisted by means of the equalizing bar.

The power is applied to the hoisting arm 11, which is integral with the frame, through the medium of the cable 12, and the point of attachment of said cable on said hoisting arm being at any of the apertures in the length thereof, and depending upon the point of attachment of the equalizing bar or cable which supports the load on the crane arm, enables the point of attachment of the cable to be substantially in line with the center of gravity of the load to be lifted. The crane arm may be held from swinging if desired during a hoisting operation, by a turn of cable or line thrown around the hoisting arm and crane arm, which may be quickly released when the load has reached the desired elevation. As the load is elevated by the crane 9, the pawl 17, clicks over the ratchet teeth in the guide-way in position to instantly support the frame and load in case of accident or failure of the cable 12, or the operating mechanism there-

for. When the desired floor is reached the crane arm is swung laterally and inwardly, and the load is deposited upon a low car or truck, or upon rollers provided therefor, to be drawn to any desired point by means of the cable 30, which is passed through suitable snatch blocks connected at convenient points, and thence looped around the drum 28, at that floor and as the cable is wound up by the drum the cable is coiled beside the same as clearly shown in Figs. 1, 2, and 3. After depositing the load upon the floor of the building the hoisting crane may be returned for re-loading by tripping the pawl 17. When the guide-way frame is extended for the next upper floor it is only necessary to build on an additional section and to shift the hoisting beam upwardly to engage the top thereof, as before described, to enable the device to be used for the next succeeding floor, and this extension can be effected without material delay or interference with the use of the device. Likewise a section of the shaft 25, may be inserted in place as the floors are built up.

I have only shown a distributing mechanism connected for use on the upper floor of the building, but it is obvious that any number of such mechanisms may be used simultaneously on each floor of the building.

Of course it is to be understood that I have only shown a preferred form of my invention, although the invention is obviously capable of numerous variations and modifications from the particular and preferred embodiment illustrated and described herein. I therefore do not purpose limiting the patent granted otherwise than necessitated by the prior art.

I claim as my invention:

1. In a device of the class described a power driven winch for a hoisting machine, a vertically movable frame operated thereby to elevate its load thereon, a vertical shaft operated from a suitable source of power with the winch, drums thereon at intervals in the length thereof adapted to receive a cable therearound whereby a load elevated by the hoist may be delivered by said cable from the hoist.

2. The combination with a building frame-

work, of a guide-way connected thereto, a crane arm movably mounted on said guide-way to elevate a load of material, a winch for elevating said crane, a source of power 55 for driving the same, a vertical shaft driven from the same source of power with the winch, drums on said shaft at each floor of the building, and snatch blocks disposed about the building framework and adapted 60 to receive a cable from said drums for engagement with the load when deposited from the crane at the different floors of the building to haul the load thereover.

3. In a device of the class described a 65 sectional elevator construction, elevating means, driving means therefor, a sectional driving element adapted to be built up simultaneously with said elevator construction and driven by said driving means, and 70 means connected to said element on each floor adapted to receive the load from the elevating means and transfer it from place to place.

4. A device for handling material in a 75 building under construction comprising the combination of elevating means on the exterior of the building, means permitting said elevating means to be swung into any story of the building, a transferring element 80 on each story of the building to coöperate therewith in disposing of the material, and a common driving mechanism for said elevating means and transferring elements.

5. In a device for handling material in 85 a building under construction, sectional elevating means adapted to be built up with each floor of the building, transferring means for the building at each floor thereof, a sectional driving element adapted to be 90 built up together with said elevating means to drive said transferring means at the different floors of the building, and a common driving mechanism for said elevating means and transferring means.

In testimony whereof I have hereunto subscribed my name in the presence of two subscribing witnesses.
